(57) **CLAIM**

The ornamental design for a wheel, as shown and described.

DESCRIPTION

FIG. 1 is a right, front, and top perspective view of an embodiment of a wheel;

FIG. 2 is a left, rear, and top perspective view of the wheel of FIG. 1;

FIG. 3 is a front elevational view of the wheel of FIG. 1;

FIG. 4 is a right elevational view of the wheel of FIG. 1;

FIG. 5 is a rear elevational view of the wheel of FIG. 1;

FIG. 6 is a left elevational view of the wheel of FIG. 1;

FIG. 7 is a top plan view of the wheel of FIG. 1; and,

FIG. 8 is a bottom plan view of the wheel of FIG. 1.

The broken line showing of a hub and spacer in FIGS. 1-8 is included for the purpose of illustrating environment and forms no part of the claimed design.

1 Claim, 8 Drawing Sheets
